ENGINE STARTING APPARATUS

Lawrence C. Dermond, Anderson, Ind., assignor
to General Motors Corporation, Detroit, Mich.,
a corporation of Delaware

Original application August 4, 1940, Serial No.
351,303, now Patent No. 2,326,125, dated August
10, 1943. Divided and this application July 6,
1942, Serial No. 449,857

14 Claims. (Cl. 290—38)

This invention relates to starting apparatus for internal combustion engines, more particularly to those of automotive vehicles, and especially to the automatic and semi-automatic types of starting apparatus in which the starter circuit is automatically closed by closing of the ignition switch, or is closed by operation of some one of the control instrumentalities of the vehicle such as the accelerator pedal, or clutch pedal, and is held open by the effect of suction when the engine runs under its own power.

This application is a division of Serial No. 351,303, filed August 4, 1940, which has now been issued as Patent No. 2,326,125, August 10, 1943.

In starting apparatus of the kind above referred to, some difficulty has been encountered in providing a suitable suction controlled switch due to the difficulty of constructing a switch sufficiently sensitive to be operable by the manifold vacuum under all operating conditions when the engine is running under its own power to break the circuit and which yet will not be operable by the vacuum when the engine is being operated by the starting motor during the cranking period before such engine becomes self-operative. It is obvious that under certain operating conditions the vacuum effective on such a switch will become quite low during the operation of the engine on its own power and will approach, if not actually equal, the vacuum which is maintained in the manifold when the engine is being turned over by the starting motor before it actually becomes self-operative and it is this condition which brings about the difficulty referred to.

It is, therefore, the primary object of the present invention to provide in a starting apparatus of the character referred to, a control switch which cannot be opened by engine suction during the cranking period, but will be maintained in its open position at all times and under all conditions when the engine is running under its own power, either when operating under load or when idling.

With this object in view, one feature of the present invention consists in the provision of a control switch having a suction operated member which is operable in conjunction with a member operable manually and simultaneously with the carburetor throttle to control the opening and closing of the switch contacts, such contacts being maintained in open position when the engine is not running by the position of the manually operable device and being prevented from closing at all times when the engine is in

operation by the suction operated member which is positively maintained in a position to accomplish this function whenever the engine operates under its own power.

5 The manually operable member, above referred to, is moved as the throttle is moved toward open position to allow the closing of the starter circuit and the suction immediately becomes effective on the suction operated member as the engine is cranked, but the device is so constructed that such suction operated member cannot be moved to a position where the switch contacts would be open by any degree of suction which can possibly be produced during the cranking operation. In fact, in one form of the invention the manually operable member must be restored to its normal position by restoration of the throttle to its normal, or idling, position, thus manually opening the circuit before the suction can be effective to so move the suction operated member to the position where it holds the circuit open.

15 In the form of the invention which is claimed herein, the device is so constructed that this manual operation to open the starter circuit is not necessary, but means are provided to prevent any movement of the suction-operated member until the suction becomes far greater than any which can be produced during the cranking period.

20 Further objects and advantages of the present invention will be apparent from the following description, reference being had to the accompanying drawings, wherein a preferred embodiment of the present invention is clearly shown.

25 In the drawings:
Fig. 1 is a diagrammatic view of a semi-automatic starting system in which the present invention is employed and showing the control switch in vertical section.

30 Fig. 2 is a fragmentary view showing the control switch in section with the parts in a different position than in Fig. 1.

35 Fig. 3 is a view similar to Fig. 2 and showing the parts in a still different position.

40 Fig. 4 is a vertical, sectional view partly in elevation, showing a modified form of the device in which a diaphragm is employed as the suction operated member.

45 Fig. 5 is a vertical section of a modified form of the device shown in Fig. 4 in which the starter circuit does not have to be broken by a manual operation.

Fig. 6 is a horizontal view on the line 6—6 of Fig. 5.

Referring to Fig. 1 of the drawings, the starting motor which is indicated at 20 has a ground connection 22 and an armature shaft 24 on which is splined a sleeve 26 which is secured to one member of an overrunning clutch 28, the other member of which is integral with a driving pinion 30 adapted to be moved into engagement with the flywheel gear 32 of the engine in order to turn said gear and start the engine whenever the starting motor is operative. The sleeve 26 is moved to the right in Fig. 1 to effect engagement of the pinion 30 with the gear 32 and the circuit between the starting motor and the battery is concurrently closed to cause the starting motor to become operative.

To this end the sleeve 26 is provided with a grooved collar 34 which is slidable on the shaft 24 and said collar is engaged by pins 35 which project from a yoke formed on the lower end of a lever 36 suitably pivoted at 38 and connected at its upper end with the armature 40 of an electromagnet 41 by means of a lost motion connection comprising a pin 42 and slot 44 which is provided for the purpose of enabling the lever and the armature to have some motion relative to each other.

When the magnet is energized, the lever 36 is rocked in a counterclockwise direction, the collar 34 compressing a spring 46 which surrounds the sleeve 26 between the collar and the clutch device 28 moves the pinion into engagement with the flywheel gear in the usual manner, the construction of the driving mechanism between the starting motor and the flywheel gear being the same as ordinarily employed in manually operated starting devices of the overrunning clutch type. A spring 47 returns the lever 36 and the parts operated thereby to normal position when the above described magnet is de-energized.

The electromagnet is provided with two coils 48 and 50 having a different number of turns for a purpose which is briefly described hereinafter, and the circuit connections with the magnet coils will also be briefly described later.

The starting motor 20 is connected by a wire 52 with a fixed contact 54 of a starting motor switch, while a second contact 56 is connected by a wire 58 with a battery indicated at 60 which is grounded at 62. A movable contact 64 is adapted to be moved into engagement with the two contacts 54 and 56 when the armature of the magnet is moved to the left in Fig. 1 to close the circuit of the starting motor.

The energization of the magnet is effected by the closing of the ignition switch and a second switch indicated in its entirety by the numeral 66, the construction of which is the principal feature of novelty of the present invention which will be described in detail later, the closing of these two switches effecting closing of a magnetic switch which is in circuit with the coils of the above described magnet.

The ignition switch has a movable contact 68 connected by a wire 70 to a wire 72 extending from the generator to the wire 58, previously referred to. The contact 68 is a double contact, one branch of which engages a fixed contact 74 to which is connected a wire leading to the ignition system and a second fixed contact 76 which is connected by a wire 78 to a binding post 80 of the switch 66. The latter is provided with a second binding post 82 which is connected by a wire 84 which extends to a winding 86 of a

relay which is grounded through the generator by means of a wire 88. Mechanism is provided to effect electrical connection between the binding posts 80 and 82, this mechanism being described in detail later and when the contact between these binding posts is thus effected, current flows from the battery through the ignition switch across the binding posts 80 and 82, through the coil 86 and to ground to energize said coil, the energization of which closes the switch to effect the energization of the main magnet. The switch above referred to comprises a fixed contact 90 which is connected by a wire 92 to the wire 58 and thus to the battery, while a movable contact 94, which cooperates with said fixed contact, is connected by a wire 96 to the coil 48 which is grounded through the connection 98 and a wire 100 connects the coil 50 with the wire 96, said coil 50 being grounded through the starting motor, as shown in Fig. 1.

It will be obvious from the above that when the ignition switch and the switch 66 are both closed, which results in the energization of the coil 86, that the contacts 90 and 94, which are normally open, will be closed and when this occurs, current will flow from the battery through the wires 58 and 92, contacts 90 and 94, and wire 96 to both coils of the main magnet, energizing the magnet and effecting the shifting of the pinion and the closing of the main starter switch as previously described.

The magnet is so constructed that one of the coils may be shunted out when the main starter switch is closed, so that during the cranking period when the starting motor is rotating the engine crank shaft, the starter switch is held closed by the force of one of the magnet coils only. This mechanism constitutes no part whatever of the present invention and all of the mechanism previously described, with the exception of the construction and operating means of the switch which has been indicated generically by the reference numeral 66, is shown and described in the copending application of John B. Dyer, Serial No. 653,983, filed January 28, 1933. In view of this complete disclosure and the fact that the specific arrangement of the circuit and construction of the magnet and starter drive are not portions of the present invention, it is believed unnecessary to describe this device further, other than to state that the generator is indicated at 102 and is connected through the wire 88 with the relay coil 86, such wire connecting with the generator between the latter and the usual cut-out relay, so that when the generator is in operation, when the engine is running under its own power, the generator will build up a counter-voltage in the coil 86 and will effect the opening of switch contacts 90 and 94 in the event that for any possible reason the suction operated switch, which will be described later, would fail to act.

Coming now to the construction of the switch which has been previously designated generically as 66, it will be noted that the mechanism of this switch is positioned within housing 118, which is adapted to be mounted in any suitable way and adjacent to intake passage 112 of the carburetor, which is adapted to be connected to the engine intake manifold in the usual way. The housing is connected at its upper end to a suction conduit 114, one end of which is designed to be connected to the intake manifold at any point between the carburetor throttle and the engine intake ports. The throttle of the carburetor is indicated at 116 and is secured to an operating shaft 118, which is

journalled for rotation in the carburetor housing. This shaft may be so constructed as to extend into the switch housing 68, as indicated in the drawings, or may be connected to operate a separate shaft which extends into such housing, but in either event, the shaft which so extends into the switch housing is adapted to have secured thereto for rotation therewith, a block of insulating material 120, which has a projection 122 formed thereon, the remaining external surface of block 120 being cylindrical in form and having mounted thereon a cover of substantially cylindrical form 124 of metal, which, of course, is separated from the operating shaft by the insulating material 120. A stationary contact piece 126 is adapted to engage the metal surface 124, as shown in the drawings. This contact piece is of angular form and at its lower end is secured by a rivet 128, or in any other suitable way, to a plate 130, which forms the lower end of the housing and is made of suitable insulating material. The binding post 82 is screwed into a metal bracket 132 also of angular form, and secured by the same rivet 128 to the piece of insulating material 130.

The other binding post 80 is screwed into a similarly shaped angular bracket 134, which is secured by a rivet 136 to the plate of insulating material 130 and such rivet also secures to this plate of insulating material a flexible contact member 138, which has formed thereon a lug 140 adapted to be engaged by the projection 122, previously referred to, the normal position of the parts being such as shown in Fig. 1.

The suction conduit 114, heretofore referred to, communicates with a cylinder 142 formed on the top of the housing and having slidable therein a piston 144. At the bottom of this piston is a cylindrical portion 146 of the same size as the piston proper and separated therefrom by a groove or channel 148, into which is adapted to project, when the switch is closed, the bent-over end 150 of the flexible switch element 138. The normal lowest position of the piston is that shown in Fig. 1, and in such position it is adapted to rest upon a pin 152 which is secured in the housing.

The lower cylindrical portion 146 of the piston 144 is provided with one or more grooves 154 in which, under certain conditions, the bent-over end 150 of the contact member 138 is adapted to engage, as hereinafter more fully set forth.

The operation of this switch mechanism is substantially as follows. When the engine is not running and the parts are in their normal position with the carburetor throttle in its substantially closed, or idle, position, as shown in Fig. 1, the switch is opened because the projecting lug of insulating material 122 engages the lug 140, as shown, and no current can pass through the switch. However, when the throttle is moved toward open position in a counterclockwise direction of movement, the lug 122 is moved out of engagement with the lug 140 and the parts are permitted to assume the position shown in Fig. 3. In this position the lug 140 is permitted to move to the right and to engage the metal element 124, so that current can pass from the battery through the ignition switch and the various circuit connections to the element 138, thence through the metal element 124 to the stationary contact 126 and from there through the associated binding post and wire 84 to the coil 86 and thence to ground. This will effect the energization of the main magnet and cause the starting motor to become operative as previously described. In order to bring about this

action, the throttle has only to move partly to its full open position, a matter of 20° or thereabouts, as indicated in Fig. 3.

The parts will remain in this position as the starting motor cranks the engine for starting purposes and the suction which is effective on the piston 144 cannot lift the piston because the bent-over portion 150 of the flexible contact member is engaged in the groove 148 at this time, thus holding the piston in its lowermost position. When the device is constructed as illustrated in the first three figures of the drawings, even the suction which is effective on the piston after the engine begins to run is insufficient to overcome the action of the part 150 and the piston is held in its lowermost position as shown in Fig. 3 until the throttle is manually restored to its normal idle position, upon which operation the element 120 is reversely rotated so that the lug 122 again engages the lug 140 which will manually open the switch and also move the bent-over toe 150 back to the position shown in Fig. 1, so that the suction will then be effective to move the piston upwardly. Of course, this opening of the switch contacts will cause the starting motor to become inoperative, but the engine has been started and is running under its own power and as long as the throttle remains in its nearly closed, or idle position, the piston 144 will be held in its uppermost position for the reason that the vacuum effective on the piston is greater when running under idling conditions than at any other time.

It is well known that if the throttle is opened to accelerate the engine, a drop in the manifold vacuum occurs and since the opening movement of the throttle is accompanied by a movement of the lug 122, means must be provided to prevent the flexible contact member from taking the position shown in Fig. 3 when such opening movement of the throttle occurs. This is accomplished by means of the lower cylindrical portion 146 of the piston. As the piston drops, due to a fall in suction upon an opening movement of the throttle, the cylindrical portion of such piston 146 is brought to a position opposite the bent-over portion 150 of the flexible contact, so that it is engaged thereby as indicated in Fig. 2, and this portion of the piston is also provided with the groove 154 so that the element 150 will enter such groove. When this takes place, a further downward movement of the piston is prevented, so that it cannot drop to a position where the large groove 48 is opposite the part 150, but remains held in the position where the toe 150 engages the groove 154 as long as the engine continues to run, or until the throttle is restored to normal idling position, in which event the piston would be raised and the toe 150 disengaged from the groove 154 by the engagement of lug 122 with lug 140. However, if this takes place and the throttle is again opened for acceleration, the operation above described would be repeated and the toe 150 would again engage the groove 154 to prevent any possible closing of the circuit through the switch.

The device shown in Fig. 4 of the drawings is the same as shown in Fig. 5 in its general characteristics, the only difference being the construction of the flexible contact member and the piston so that although one of these is a somewhat modified form of the invention, reference may be had to both figures for such disclosure as is common to the two.

Referring particularly to Fig. 4, it will be noted

that a boss 160 is formed on the carburetor intake housing and a switch housing 162 is secured to such boss in any suitable way. A shaft 164, on one end of which the throttle 166 is mounted, is journalled for rotation in the carburetor housing and at its other end carries a cam element 168 of suitable insulating material and having a lug 170 formed thereon similar to the lug 122, previously referred to. This element 168 is surrounded, except for the lug 170, by a generally cylindrical metal sleeve 172 and is secured on the end of the throttle shaft in any suitable way, as by means of a nut 174. A fixed contact member 176 engages the surface 172 and corresponds to the contact 126 previously described, this contact being connected with a binding post 178 which is secured to the housing 162 in any suitable manner, and separated therefrom by pieces of insulating material 180. A flexible contact member 182 which corresponds to the element 138 is suitably secured to the housing 162 and insulated therefrom by a piece of insulating material 184, while electrically connected to the contact element 182 is a binding post 186, which is also suitably secured to the housing and separated therefrom by a piece of insulating material 188.

The only material difference between this form of the switch device and that previously described resides in the fact that the suction operated element is a diaphragm instead of a piston and to this end a diaphragm 190 is secured between a flange 192 formed on the housing 162 and a corresponding flange 194 formed on a cover plate 196 which is secured to the housing 162 in any suitable manner, as by means of machine screws 198. The diaphragm is held in its lower position by a spring 200 received between itself and the cover plate and suction is communicated to the space above the diaphragm by means of a suction passage 202 formed in the boss and in the wall of the housing 162 and cover plate as shown in Fig. 4. Secured to the center of the diaphragm is a piston 204, such piston being supported by a rivet 206, which extends through the diaphragm and clamps together a washer 208 which is below the diaphragm, the diaphragm itself, and a cup-shaped element 210 located above the diaphragm and which receives the lower end of the spring 200 above referred to, the elements 208 and 210 and the diaphragm being held in a rigid assembly by means of the rivet 206, which has at its lower end an enlarged head 212 which carries the piston 204, above referred to. The piston 204 is provided with a reduced portion at its upper end which is adapted to lie opposite the flexible contact member when the parts are in normal position in the same manner as does the groove 148 previously described, while the outer surface of the piston 204 is provided with a plurality of grooves 214 with which the bent-over end of the flexible contact piece which corresponds to the bent-over portion 150 of contact piece 138 is adapted to engage in just the same way as previously set forth to prevent the closing of the contacts of the switch when the engine is running and also to prevent the piston from ever assuming the position where the contacts can be closed during self-operation of the engine.

The operation of this piece of mechanism is exactly the same as that previously described. In its normal position, the flexible contact element is opposite the lug of insulating material which holds the switch open, but upon movement of the throttle toward open position, the contacts are

allowed to close and when the engine commences to run, the suction which is communicated through the suction conduit to the diaphragm lifts the piston 204 to bring about the same results as have previously been described in connection with the device shown in Figs. 1 to 3.

In the slightly modified form of the invention shown in Fig. 5, there is only one difference in construction and one difference in the result produced from what has previously been set forth. It will be noted upon examination of this figure that at the upper end of the piston, 204, which is shown in Fig. 5, is a tapered instead of an abrupt shoulder, such shoulder being indicated at 220, and the upper end of the flexible contact member 182 instead of having a bent-over toe is curved in a manner to be substantially parallel to the surface 220 as indicated at 222. With this construction, when the engine starts to run with the parts in the position corresponding to Fig. 3, so that the flexible contact member 182 engages the piston, the surfaces 220 and 222 are in engagement. The effect of the suction during cranking is insufficient to lift the piston because of the friction between the parts, but when the engine starts to run with the throttle in only a partially open position, the suction effective on the diaphragm is sufficient to pull the piston upwardly, overcoming the friction referred to and this action will break the circuit through the switch. As the piston is lifted, the surface 222 will contact with one of the grooves and will act as a spring detent holding the piston in its upper position and the piston in turn prevents the circuit from being made through the switch contacts. Thus, in this particular form of the device, the circuit is actually broken by the action of engine suction when that suction is sufficiently high, but so great a degree of suction is required to effect this result that it is only under certain operating conditions that such result is possible and it is never possible during cranking. However, with this type of device, the piston prevents any possible closing of the switch during the operation of the engine under its own power and the device is so constructed that only a relatively high degree of engine suction can cause the lifting of the piston and the breaking of the circuit.

While the embodiment of the present invention as herein disclosed, constitutes a preferred form, it is to be understood that other forms might be adopted, all coming within the scope of the claims which follow.

What is claimed is as follows:

1. In a starting apparatus for internal combustion engines having a current source, a starting motor operable by current from said source and a circuit for connecting said starting motor with the current source, a switch for controlling said circuit, means for operating said switch, a control member movable to two positions in one of which it prevents closing of the switch and in the other of which it permits said switch to be closed to cause operation of the starting motor, means operable by the engine when it becomes self-operative to move said control member to a position where it prevents closing of the switch, and means engaging said control member for preventing such movement of the control member while the engine is being operated by the starting motor and for preventing the return of said control member to a position where it permits closing of the switch as long as the engine is self-operative, said

means for engaging the control member being ineffective to prevent movement of the control member to a position where it prevents closing of the switch whenever the engine begins to operate under its own power.

2. In a starting apparatus for internal combustion engines having a current source, a starting motor operable by current from said source and a circuit for connecting said starting motor with the current source, a switch for controlling said circuit, means for operating said switch, a control member movable to two positions in one of which it prevents closing of the switch and in the other of which it permits said switch to be closed to cause operation of the starting motor, means operable by the engine when it becomes self-operative to move said control member to a position where it prevents closing of the switch, and a latch member for preventing movement of the control member while the engine is being operated by the starting motor and for preventing the return of said control member to a position where it permits closure of the switch as long as the engine is self-operative, said latch member being ineffective to prevent movement of the control member when the engine begins to operate under its own power.

3. In a starting apparatus for internal combustion engines having a current source, a starting motor operable by current from said source and a circuit for connecting said starting motor with the current source, a switch for controlling said circuit, means for operating said switch, a control member movable to two positions in one of which it prevents closing of the switch and in the other of which it permits said switch to be closed to cause operation of the starting motor, means operable by engine suction when the engine begins to run under its own power to move said control member to a position where it prevents closing of the switch, and a latch member for preventing such movement of the control member while the engine is being operated by the starting motor and for preventing return of the control member after it is moved by engine suction as long as the engine is self-operative, said latch member being ineffective to prevent movement of the control member by engine suction when the engine begins to run under its own power.

4. In a starting apparatus for internal combustion engines having a current source, a starting motor operable by current from said source and a circuit for connecting said starting motor with the current source, a switch for controlling said circuit, means for operating said switch, a suction operated piston for controlling operation of the switch normally in position to permit closing of said switch and movable to a position to prevent closing of said switch when the engine begins to run under its own power, and a latch engaging said piston and preventing its movement while the engine is being operated by the starting motor, said latch being ineffective when the engine starts to operate under its own power.

5. In a starting apparatus for internal combustion engines having a current source, a starting motor operable by current from said source and a circuit for connecting said starting motor with the current source, a switch for controlling said circuit, means for operating said switch, a suction operated piston for controlling operation of the switch normally in position to permit closing

of said switch and movable to a position to prevent closing of said switch when the engine begins to run under its own power, and a latch engaging the piston to prevent its movement by suction while the engine is being operated by the starting motor and also operable to engage the piston after it has been moved by suction to prevent the return of the piston to a position where it permits closing of the switch while the engine is self-operative, said latch being ineffective to hold the piston against movement by suction when the engine begins to operate under its own power.

6. In a starting apparatus for internal combustion engines having a current source, a starting motor operable by current from said source and a circuit for connecting said starting motor with the current source, a switch for controlling said circuit, means for operating said switch, a suction operated piston for controlling operation of the switch normally in position to permit closing of said switch when the engine begins to run under its own power, a latch engaging the piston to prevent its movement by suction while the engine is being operated by the starting motor and also operable to engage the piston after it has been moved by suction to prevent the return of the piston to a position where it permits closing of the switch while the engine is self-operative, said latch being ineffective to hold the piston against movement by suction when the engine begins to operate under its own power, and means operable by the switch operating means for disengaging the latch from the piston under certain operating conditions.

7. In a starting apparatus for internal combustion engines having a current source, a starting motor operable by current from said source and a circuit for connecting said starting motor with the current source, a switch for controlling said circuit, means for operating said switch, a suction operated piston for controlling operation of the switch normally in position to permit closing of said switch and movable to a position to prevent closing of said switch when the engine begins to run under its own power, a latch engaging the piston to prevent its movement by suction while the engine is being operated by the starting motor and also operable to engage the piston after it has been moved by suction to prevent the return of the piston to a position where it permits closing of the switch while the engine is self-operative, said latch being ineffective to hold the piston against movement by suction when the engine begins to operate under its own power, and means operable by the switch operating means, when such means is moved to normal position to effect opening of the switch, to disengage the latch from said piston to permit the piston to move to its normal position.

8. In a starting apparatus for internal combustion engines having a current source, a starting motor operable by current from said source and a circuit for connecting said starting motor with the current source, a switch for controlling said circuit, means for operating said switch, a suction operated piston controlling operation of said switch, movable to a position to prevent closing of said switch when the engine begins to run under its own power and provided with a shoulder, and a latch engaging said shoulder to prevent movement of the piston by suction while the engine is being operated by the starting motor, said latch being ineffective to hold the piston

against the force of the suction when the engine starts to run under its own power.

9. In a starting apparatus for internal combustion engines having a current source, a starting motor operable by current from said source and a circuit for connecting said starting motor with the current source, a switch for controlling said circuit, means for operating said switch, a suction operated piston controlling operation of said switch, movable to a position to prevent closing of said switch when the engine begins to run under its own power and provided with a shoulder and a latch engaging said shoulder to prevent movement of the piston when the suction is low and for engaging another portion of the piston to prevent the return of the piston to normal position after it has been moved by suction, said latch being ineffective to hold the piston against the force of suction when the engine begins to operate under its own power.

10. In a starting apparatus for internal combustion engines having a current source, a starting motor operable by current from said source and a circuit for connecting said starting motor with the current source, a switch for controlling said circuit, means for operating said switch, a suction operated piston controlling operation of said switch, movable to a position to prevent closing of said switch when the engine begins to run under its own power and provided with a shoulder, and a resilient latch member engaging said shoulder with sufficient force to hold said piston against movement by suction when the engine is being operated by the starting motor but incapable of exerting a sufficient force to hold the piston against movement by suction when the engine starts to run under its own power.

11. In a starting apparatus for internal combustion engines having a current source, a starting motor operable by current from said source and a circuit for connecting said starting motor with the current source, a switch for controlling said circuit, means for operating said switch, a suction operated piston controlling operation of said switch, movable to a position by suction to prevent closing of the switch and provided with a shoulder and a groove on the surface, and a latch engaging said shoulder to hold the piston against movement at low suction but ineffective to hold said piston against movement when the engine starts to run under its own power, said latch being also operable to engage said groove when the piston has been moved by suction to retain the piston in the position to which it has been moved.

12. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, said control member being engageable by one of said switch contacts when the switch is closed to prevent movement of said control member when the engine is being operated by the starting motor and said contact being ineffective to hold the control when the engine starts to run under its own power.

13. In a starting apparatus for internal combustion engines having a current source, a starting motor operable by current from said source and a circuit for connecting the starting motor with said current source, a switch for controlling said circuit and provided with a plurality of contact members, a control member movable by engine suction to a position to prevent closing of the switch when the engine becomes self-operative, said control member being engageable by one of said switch contacts when the switch is closed to prevent movement of said control member when the engine is being operated by the starting motor and said contact being ineffective to hold the control when the engine starts to run under its own power, and manually operable means to cause movement of the last named switch contact to a position where it engages the control member and closes said switch.

14. In a starting apparatus for internal combustion engines having a current source, a starting motor operable by current from said source and a circuit for connecting the starting motor with said current source, a switch for controlling said circuit, a carburetor for supplying combustible mixture to the engine and a throttle valve for regulating the mixture flow, means operable manually in conjunction with the throttle valve to operate the switch, means operable by engine suction to prevent closing of the switch when the engine is self-operative and means other than the manually operable means for preventing operation of the suction operated means when the control switch is closed and the engine is operated by the starting motor, said means being ineffective when the engine begins to operate under its own power.

LAWRENCE C. DERMOND.
